UNITED STATES PATENT OFFICE.

WILLIAM G. CHENEY, OF MARLBORO, MASSACHUSETTS, ASSIGNOR TO UNITED SHOE MACHINERY CORPORATION, OF PATERSON, NEW JERSEY, A CORPORATION OF NEW JERSEY.

DEVICE FOR LAYING AND INDENTING RUBBER FOXING.

1,413,707.

Specification of Letters Patent. Patented Apr. 25, 1922.

Application filed April 21, 1919. Serial No. 291,455.

To all whom it may concern:

Be it known that I, WILLIAM G. CHENEY, a citizen of the United States, residing at Marlboro, in the county of Middlesex and State of Massachusetts, have invented certain Improvements in Devices for Laying and Indenting Rubber Foxing, of which the following description, in connection with the accompanying drawings, is a specification, 10 like reference characters on the drawings indicating like parts in the several figures.

This invention relates to the manufacture of boots and shoes and has particular reference to the production of vulcanized rubber sole articles such as tennis shoes, sneakers and arctics. In the manufacture of such articles a strip of high-grade rubber compound termed "foxing" is customarily employed as an intermediate connection between the outsole member of the shoe and its upper for the purpose of securing the necessary vulcanization of those parts together. Before placing the foxing in position, cement is applied along portions of 20 the upper and outsole. So far as I am aware, the practice has always been to place the strip of foxing along the cement-coated portions of the shoe and then to run a heavy hand roller back and forth along the 25 strip to ensure proper contact of the foxing with the cement in order that the later vulcanizing operation may effect a secure and completely waterproof joint. It has also been the practice to produce the appearance of a line of stitches along the edge 30 of the foxing which overlaps the portion of the upper above the shoe bottom, this operation being effected by the manual use of a serrated wheel called a "stitch wheel". The two operations of rolling or "laying" 35 the foxing by the hand roller referred to and producing the stitch line are effected in succession, requiring not only considerable time and manual effort, but also skill in so guiding the stitch wheel that the line produced 40 will be close to and just within the margin or edge of the foxing strip.

An important object of the present invention is to avoid the loss of time resulting from separate operations of rolling or laying the foxing and then stitch-indenting it. With this object in view, the invention in one aspect comprises a rotary wheel having a toothed portion to produce a line

of indentations and having also a smooth 55 foxing-laying portion of such shape that it will sufficiently conform to the portions of the lasted shoe underlying the foxing to materially aid the operator in so guiding the shoe that the stitch line will be properly 60 located.

Another important object of the invention is to provide a rotary foxing applying device the rotation of which will be automatically stopped if there is such a protuberance in the foxing as might arrest feed 65 of the work and result in cutting into the foxing.

With these and other objects in view and in accordance with important features of 70 the invention, the illustrated machine comprises a stitch-indenting wheel and an adjoining rolling or laying member which is preferably elastic, both the wheel and said member being frictionally rotated. In the 75 illustrated embodiment of the invention, I have provided also a guiding roll adapted to engage the bottom of the sole and guide the shoe to the laying and indenting tool, said roll being mounted to enable the work 80 to be presented to the tool at the required angle.

I have so far referred to the machine as useful for laying and stitch-indenting foxing. It is also adapted for the laying and 85 stitch-wheeling of the margins of the outsoles of rubber footwear as will become more apparent hereinafter.

In the drawings,

Fig. 1 is a perspective view of the 90 machine.

Fig. 2 is a sectional elevation illustrating the operation of the machine.

Fig. 3 is a sectional view of the operating tool illustrating its mounting upon the driving shaft.

Fig. 4 is an elevation of the toe portion of a shoe which has been operated upon by the tool.

A suitable frame standard 12 is formed 100 or provided at its upper end with a bearing 13 for a shaft 14, which may be driven by any suitable means such as a belt running on a pulley 15.

The other end of the shaft is reduced as at 105 16 (Fig. 3) to provide a shoulder 17. Secured to the shaft adjacent the shoulder 17 is a disk 18. Fitted to the shouldered por-

tion of the shaft 14 is the base member 19 of a cylinder, the main portion of which is slotted or split to form a series of parallel tongues 20. The outer ends of the tongues 5 rest upon a reduced portion of a disk 21, the periphery of which is milled or formed with teeth to indent the rubber material as herein-after described. The wheel 21 is mounted upon the outer end of the reduced portion 10 of the shaft so that it may rotate thereupon when the friction is overcome as herein-after described, said wheel 21 being held in place by a washer 22 through which a screw 23 passes into the end of the shaft. A spring 15 24 coiled about the reduced portion of the shaft bears at its opposite ends against the base 19 of the split cylinder and against the reduced portion of the wheel 21, said spring serving to hold frictionally the base 20 member 19 against the shoulder 17 of the shaft and also to cause such friction between the wheel 21 and the washer 22 as to cause rotation of the wheel 21 excepting at such 25 times as opposition to its rotation, as herein-after described, may hold the wheel stationary while the shaft continues to revolve.

Mounted on the cylinder 20 and confined between the disk 18 and the wheel 21 is a laying or pressing member in the form of a 30 roll 25, preferably of rubber. Preferably the exterior of the roll 25 is such that its outer end has a somewhat concave tapering formation so that when work is applied thereto, the laying member 25 will somewhat 35 conform to the transverse shape of the portion of the shoe to be operated upon as illustrated in Fig. 2.

The object of having the stitch-indenting wheel 21 on the laying roll 25 so mounted 40 upon the shaft as to be frictionally driven thereby is to prevent liability of the work being cut into if a thick portion, such as would result from the overlapping of the 45 ends of the foxing, were to be pressed up too firmly against the wheel as the work is being fed along. If such a thickened portion reaches the wheel 21 while the operator is holding the work in the position shown in Fig. 2, the wheel will be stopped, owing to 50 the protuberance of the foxing, giving the operator an opportunity to move the work slightly away from the wheel and permit it to pass the protuberance without cutting into it. To enable the operator to present 55 the work to the tool 21, 25 at the required angle, and yet hold the work steadily at such angle as the operator feeds the work along, I provide a guide roll 26 mounted in a yoke 27 pivotally connected at 28 to a stud 60 29 which is reciprocably mounted in a sleeved bearing 30, the latter having slots 31 into which a pin 32 secured transversely in the stud 29 projects, so that said stud may shift endwise in the sleeve or bearing, but 65 not rotate therein. A spring 33 within the

sleeve or bearing 30 bears at one end against a collar 34 which is secured by the pin 32 to the stud 29 and at the other end against a suitable stop shoulder formed in the sleeve. 70

The sleeve or bearing 30 is provided with a flange 35 bearing against vertical guides at the inner side of a slot 36 formed in the head of standard 12. By means of a nut 37 fitted to a threaded portion of the sleeve 75 or bearing, said sleeve or bearing may be vertically adjusted to vary the distance of the guide roll 26 from the tool 21, 25.

The stud 29 and the guide roll 26 carried thereby may shift to the right from the position shown in Fig. 2 against the action of spring 33, provided the operator presses the work with sufficient force against the roll 26 in order to present the work at the proper angle to the tool 21, 25. The outer 80 limit toward the left from the position shown in Fig. 2 to which the stud and roll 26 may be shifted by the spring 33 is determined by a nut 38 fitted to the end of stud 29 which passes through the hub portion of 85 the bearing or sleeve 30.

A suitable guide for a strip of foxing which may be led from any suitable source of supply is indicated at 39, said guide being carried by an arm 40 adjustably mounted in 90 a clamp 41 carried by the upper end of a rod 42 which is adjustably secured by any suitable means to the head of the standard 12.

In operation, whether the strip of foxing has been completely located around the cement bearing portion of the shoe before 100 using the machine, or is led through the guide 39 on to the shoe, the operator holds the work in substantially the position shown in Fig. 2 with the sole of the lasted shoe 105 bearing against the guide roll 26, and he then either feeds the work along or permits it to be fed by the tool while holding the work firmly against the tool so that the laying member 25 of the tool will effect complete and uniform contact of the foxing with the underlying cemented portion of the shoe while at the same time the wheel 21 produces the appearance of a line of stitches in the edge portion of the foxing which extends partly up over the sides of the upper. Since the guide roll 26 is yieldingly mounted, the work can be pushed back so that the transverse angle of the sole portion of the shoe may vary more or less relatively to the 110 axis of rotation of the tool 21, 25 in order to operate upon the desired portion of the foxing. Owing to the yoke 27 being pivotally connected to the stud 29, the said roll 26 will tilt in conformity with the particular 115 angle at which the work is fed along.

Owing to the fact that the operator causes the work to bear against the tool with considerable pressure, he would be liable to continue the feed if the foxing presented some 120

protuberance such as results from overlapping the ends of the foxing. Owing to the frictional mounting of the tool, however, if any such protuberance reaches the tool, it stops the tool from rotating until the operator can relieve the pressure sufficiently to enable the protuberance to pass along without being cut into.

In Fig. 4 I have indicated a portion of a shoe upper *a* and foxing *b* and outsole *c*, these parts being also shown in section in Fig. 2. After the foxing has been laid and stitch indented as described, the same tool or machine can be used for rolling over the marginal portions of the outsole and stitch indenting the edge thereof. In doing this, the outsole is laid in place and held there by the usual cement which is employed on the innersole, and the work then manipulated in the manner described so that the laying member 25 of the tool will turn up and roll down the marginal portions of the outsole while the wheel 21 simultaneously forms the appearance of a line of stitches as indicated in Fig. 4.

Having described my invention, what I claim is:—

1. A machine of the class described, having in combination, a combined laying and indenting tool comprising a roll having a concavity therein shaped to conform substantially to the convexity at the lower margin of a lasted shoe and a toothed disk adjacent the roll, and means for rotating the tool.

2. A machine of the class described, having in combination, a combined laying and indenting tool comprising an elastic roll having a concavity therein shaped to conform substantially to the convexity at the lower margin of a lasted shoe and a toothed disk adjacent the roll, and means for rotating the tool.

3. A machine of the class described, having in combination, a combined laying and indenting tool comprising a roll of yielding material having one end of less diameter than the other and a toothed disk located at the end of the smaller diameter, and means for rotating the tool.

4. A device of the character described comprising an elastic rotary roll, a toothed disk adjacent the roll, and means for frictionally operating the disk and roll.

5. A machine of the class described, having in combination, a combined foxing laying and indenting tool comprising an elastic pressure member having a concavity to receive the convexity at the lower margin of a lasted shoe and to contact with the body of the foxing and an indenting member located to engage the upper edge of the foxing, and means for operating the tool.

6. A machine for operating upon a rubber soled shoe provided with a foxing having, in combination, a foxing-laying roll having a periphery shaped to correspond substantially to the transverse curvature of the lower margin of the shoe, a stitch-indenting wheel at the end of the roll, and shoe-guiding means adapted to facilitate the presentation of a shoe in such manner that the foxing is laid against the upper by the roll and a line of imitation stitches is impressed in the foxing along the upper edge thereof by the wheel.

7. In a machine of the character described, a shaft and a toothed disk and concavo conical roll mounted on the shaft and constructed and arranged to be frictionally rotated thereby.

8. A machine of the class described, having in combination, a combined pressing and indenting tool shaped to operate upon the lower margin of a shoe, means for rotating the tool, and a guide arranged to engage the bottom of the shoe.

9. A machine of the class described, having in combination, a combined pressing and indenting tool shaped to operate upon the lower margin of a shoe, means for rotating the tool, a guide arranged to engage the bottom of the shoe, and means whereby the guide may be adjusted in a direction substantially parallel to the axis of rotation of the tool.

10. A machine of the class described, having in combination, a combined work pressing and indenting tool comprising an elastic roll and a metallic toothed disk for operating upon the lower margin of a shoe, a guide arranged to engage the bottom of the shoe, and a spring supporting the guide.

11. A machine of the class described, having in combination, a combined laying and indenting tool, and a work guide arranged to engage the bottom of a shoe to aid in presenting the lower margin thereof to the tool, said guide comprising a spring-pressed rod, a yoke pivoted to said rod, and a roll mounted in the arms of the yoke.

12. A machine of the class described, having in combination, a rotary indenting wheel, and a guide for a shoe constructed and arranged to cause the wheel to operate upon the margin of the shoe above the bottom thereof, said guide comprising a rod slidable in a direction substantially parallel to the axis of rotation of the wheel, a yoke pivoted to the rod about an axis transverse to the axis of the rod, and a roll mounted in the arms of the yoke.

In testimony whereof I have signed my name to this specification.

WILLIAM G. CHENEY.
